EGG CONTAINER

Edward H. Reeves, Jamaica, N. Y.

Application April 1, 1931. Serial No. 526,955

9 Claims. (CL 217—25.5)

This invention relates to the class of egg shipping carriers, boxes, cases and containers having fillers to retain the eggs against breakage from handling and while in transportation.

The principal object of the invention is to provide improvements in carriers or containers of the indicated character to the end that eggs will not be broken under extremely rough handling and usage.

Another object is the provision, in a carrier or container of the indicated character, of improved means for quickly and conveniently packing the eggs and for resiliently retaining them in place separated from each other within the outer carrier or container.

Another object of the invention is the provision of packaging means for egg shipping containers which affords protection for the eggs to prevent them from being damaged or broken and at the same time keeps them from being frozen in cold weather.

With the foregoing, other objects of the invention will appear from the embodiment of the invention which by way of example is described in the following specification and illustrated in the accompanying drawing, in which

Figure 1 is a perspective view of an egg container having the features of the invention;

Figure 2 is a plan view of the container with the cover section removed and a portion of one of the pads broken away to show certain features;

Figure 3 is an enlarged section taken substantially on the line 3—3 of Figure 1.

On reference to the drawing it will be apparent that the egg container includes a carrier or case which may be of any preferred size and which may be made of any preferred material such as duralumin or fiber board. The case will be of such construction as to meet the requirements of the postal authorities and will be provided with the necessary means for accommodating the consignor's and consignee's addresses. In the present instance, the case or container consists of two sections, a receptacle section 10, and a cover section 11, in which the section 10 fits in telescopic relation. The sections 10 and 11 are held together by a strap or band 12, having any suitable securing means such as the buckle 13. The strap 12 encircles the sections 10 and 11 when they are brought together and is adapted to exert pressure on these sections.

In accordance with the main feature of the invention use is made of means capable of being arranged within the section 10 of the container or case for resiliently retaining a plurality of

eggs in place separated from each other within the container for shipment. The said means consists of a suitable number of parts of conformable resilient material. The material used will be comparatively light in weight and will have 60 the necessary modulus of resiliency and flexibility. For best results the material used is preferably of a porous or cellular nature, and, in the present instance, is sponge rubber. This is made of three parts or pads of rubber, there being a 65 top pad 14, an intermediate pad 15 and a bottom pad 16. Each of the pads corresponds in size and shape to the inside plan of the case or container section 10. All of the pads are flat in 70 formation and are arranged flatwise in relation to the other pads. The pads 14 and 16 are of equal thickness, whereas, the intermediate pad 15 is somewhat thicker than the pads 14 and 16. The pad 15 has a suitable number and arrangement of spaced openings 17 therein for the 75 eggs designated 18. In the present instance, the pad 15 has twenty-four openings 17 to accommodate two dozen eggs.

In packing the container or case consisting of the sections 10 and 11, the pad 16 is arranged 80 within the section 10. The intermediate pad 15 is placed on the pad 16. The eggs are then placed in the openings 17, end up, as shown most clearly in Fig. 3. The pad 14 is then placed over the eggs. The pad 14 will project above the upper 85 edge of the section 10. The cover section 11 is then brought down over the section 10 and the strap 12 is brought around and buckled to exert the necessary pressure on the sections 10 and 11. This will cause the portions of the pads 90 14 and 16 to be distended between the ends of the eggs and thus both pads 14 and 16 will cooperate with the pad 15 to resiliently retain the eggs against displacement out of contact with each other.

From the foregoing it will be apparent that there has been described an egg shipping container having provision enabling the packing of eggs for shipment in a quick and convenient manner; that the eggs will be protected by the pads from being damaged or broken from handling the container and also while it is being transported; and that the pads will not only prevent the eggs from being damaged or broken but will keep them from being frozen in cold weather.

I claim:

1. An egg shipping container comprising a case consisting of separate sections, pads of conformable resilient material for arrangement within one of the sections of said case, said pads consisting 110

- 5 of a top pad, an intermediate pad, and a bottom pad, said intermediate pad having openings therein arranged in spaced relation with respect to each other, whereby eggs may be placed in the openings respectively, and means to exert pressure on said sections to cause the top and bottom pads to cooperate with the intermediate pad to resiliently retain the eggs in place. 80
- 10 2. An egg shipping container comprising a case consisting of separate sections, a holder to be positioned within said case to maintain a multiplicity of eggs in spaced relation to each other, upper and lower pads each made of conformable resilient material to cooperate with the holder when they are placed in said case, and means to exert pressure on said sections which is imposed on said pads to resiliently retain the eggs in place. 85
- 15 3. An egg shipping container comprising a case consisting of telescoping sections, pads made of sponge rubber and of uniform thickness and corresponding in size and shape to the inside plan of the case, means to hold eggs ends up within the case, and said pads being disposed respectively at the top and bottom of said case for contact with the opposite ends of the eggs, and means to exert pressure on said sections to cause said pads, to cooperate with said holding means to resiliently retain the eggs in the case. 90
- 20 4. In an egg shipping container, sponge rubber parts each of a size to snugly fit flatwise in the container, and consisting of a part through which a plurality of eggs may extend crosswise with the ends thereof projecting therefrom and parts to cover the ends of the eggs, said container consisting of telescoping sections contacting with two of said parts, and means embracing said sections to exert pressure thereon which is imposed on said covering parts to resiliently retain the eggs 100
- 25 in place. 105
- 30 5. In an egg shipping container, three main flat parts of conformable resilient material, each of said parts being of a size to snugly fit flatwise in the container, and consisting of a part through which a plurality of eggs may extend crosswise with the ends thereof projecting therefrom and 110
- 35 40
- 45

parts to cover the ends of the eggs, said container consisting of telescoping sections contacting with two of said parts, and means embracing said sections to exert pressure thereon which is imposed on said two parts to resiliently retain the eggs in place. 115

6. An egg container comprising a case, pads of conformable resilient material for arrangement within said case to contact with the opposite ends of eggs placed between them within the case, said case including a section movable with respect to said pads, and means to exert pressure on said section to cause it to cooperate with said pads to resiliently retain the eggs in place in spaced relation with their ends disposed in cavities formed thereby in the pads. 120

7. An egg shipping container comprising a case, pads of conformable resilient material held in place by the walls of the case within the same for contact with opposite ends and sides of the eggs to hold them in spaced relation to each other, one of said walls being embodied by a section of the case which is movable with respect to said pads, and means to exert pressure on said section to cause its wall to co-operate with said pads to resiliently retain the eggs in place. 125

8. An egg shipping container comprising a case consisting of telescoping sections, top and bottom pads of conformable resilient material corresponding in size and shape to the inside plan of the case, said pads thus being adapted for arrangement within said case, means to exert pressure on said sections to cause them to co-operate with said pads to cause portions of the latter to be distended between the eggs to resiliently retain the eggs in place in spaced relation to each other. 130

9. An egg shipping container comprising a case consisting of separate sections, pads of sponge rubber for arrangement within said case to contact with the opposite ends and sides of a plurality of eggs to hold them in spaced relation to each other, and means to exert pressure on said sections to cause the latter to cooperate with said pads to resiliently retain the eggs in place. 135
